United States Patent Office.

GILBERT L. HUDSON, OF ROME O, MICHIGAN.

Letters Patent No. 96,434, dated November 2, 1869.

IMPROVEMENT IN CARRIAGE-SEATS.

The Schedule referred to in these Letters Patent and making part of the same.

To all whom it may concern:

Be it known that I, GILBERT L. HUDSON, of Romeo, in the county of Macomb, and in the State of Michigan, have invented certain new and useful Improvements in Seats for Carriages, Cars, &c.; and do hereby declare that the following is a full, clear, and exact description thereof, reference being had to the accompanying drawings, and to the letters of reference marked thereon, making a part of this specification.

The nature of my invention consists in the construction and arrangement of a spring-back for seats on vehicles of any description, railroad-cars, &c.

In order to enable others skilled in the art to which my invention appertains, to make and use the same, I will now proceed to describe its construction and operation, referring to the annexed drawings, in which—

Figure 1 is a front view of a carriage-seat with my improvement attached, and

Figure 2 is a view of one of the springs.

A represents a seat for a vehicle, made in any of the known and usual ways.

At the bottom of the back of the seat A are hinged two metal bars, B B, which, at their upper ends, are secured to and support the spring-back C.

On the front side of the spring-back C are attached two springs, D D, constructed in the following manner:

The inner ends of the springs D D, which are made of steel, and run lengthwise along the back C, are square, and fitted in boxes a a, which make the inner ends permanent, so that they cannot be turned.

At the ends of the back C, the springs D D are rounded, and placed in round journal-boxes, b b, so that the outer ends of the springs may be slightly turned or twisted in the same.

Outside of the boxes b b, the springs D D are turned down in a crank-form.

The cranks d d, of the springs D D, are, by means of pivoted arm-pieces E E, connected with the irons F F, at the front of the seat A, in any ordinary manner.

It will be seen, that by pressing on the back C, the arm-pieces E E and cranks d d cause the springs to twist, so that the back will yield, but as soon as the pressure is removed from the back C, the springs and back will at once resume their natural position.

Having thus fully described my invention,

What I claim as new, and desire to secure by Letters Patent, is—

In combination with a seat for vehicles, cars, &c., the hinged bars B B, back C, springs D D, arm-pieces E E, and bars F F, or their equivalents, all constructed as described, and arranged to operate substantially in the manner, and for the purposes herein set forth.

In testimony that I claim the foregoing, I have hereunto set my hand, this 27th day of August, 1869.

GILBERT L. HUDSON.
